CAR COUPLER HITCHING-PIN RETAINING MEANS

William R. Stamler, Bagdad, Ky., assignor to The Brown-Fayro Company, Johnstown, Pa., a corporation of Pennsylvania

Application November 1, 1945, Serial No. 625,968

6 Claims. (Cl. 213—188)

1

My invention relates to car couplings of the link-and-pin type such as are commonly employed to couple mine cars and other industrial cars.

In couplings of this type, the coupling pins or hitching pins have a tendency to creep or work upwards through travel of the cars over track irregularities that produce up-and-down movements of the car ends, until frequently the pin finally works upward so far that it falls out, thus resulting in wrecks.

One object of my invention is to provide a safety latch which is of simple form and which, nevertheless, will effectively prevent accidental withdrawal or working out of a hitching pin.

Another object of my invention is to provide a latch of the character referred to that will permit of the insertion of the hitching pin in the usual manner but which will automatically move into position to retain the pin against upward movement.

In the accompanying drawings which illustrate a preferred embodiment of the invention,

Figure 1 is a side view of a portion of a mine car with my invention applied thereto;

Figure 2 is a plan view thereof;

Figure 3 is an end view thereof;

Figure 4 is a side view showing the safety latch in released position and with the hitching pin partly withdrawn; and

Figure 5 is a plan view showing a modified location of the safety latch.

In the accompanying drawing, only so much of a car is shown as is necessary to an understanding of the invention. A car bumper is shown at 6, the car end at 7, the upper draw bar of the car at 8, and a portion of a coupling link at 9. These parts may all be of any conventional form.

The hitching pin extends through the top draw bar 8, through the link 9, and into the bumper 6, the other end of the link 9 being connected to another car (not shown). The pin is provided with an annular shoulder 11 and a flattened upper portion 12 by which it can conveniently be inserted and removed.

A pivoted latch member 14 is carried by a pivot pin or shaft 15 that extends through upstanding bracket members 16 that are bolted or otherwise suitably secured to the draw bar 8. As shown more clearly in Fig. 4, the latch member 14 has a weighted extension 17 that serves as a counter weight to normally hold the latch member 14 in the position shown in Fig. 1, at which position a projection 18 on the latch member 14 overlies the shoulder 11 of the hitching pin. If

2

the hitching pin starts to creep up, its shoulder 11 will engage the projection 18, and the pin will thereby be held against further upward movement. Upward thrusts of the pin will only tend to swing the latch member 14 in a clockwise direction, thereby forcing the extension 17 against the draw bar 8, and thus firmly lock the pin against further upward movement.

The pin 10 is withdrawn for the purpose of uncoupling the cars by pressing on the latch release portion 19 to rotate the latch in a counter-clockwise direction, to approximately the position shown in Fig. 4, whereupon the pin 10 can be lifted out of the coupling link. The radius of the projection 18 with respect to the axis of the shaft 15 is such that it will clear the shoulder 11 of the pin during swinging movements of the latch member 14, when the pin is in its lowest position.

In coupling the cars, the pin is inserted by dropping it straight down. The weight of the pin forces the latch out of the way and allows the pin to assume its engaged position without any other handling.

In Fig. 5, I show the latching element 14 and its supporting brackets 16 mounted farther forwardly on the draw bar 8 and to one side of the hitching pin, instead of at the rear side of the hitching pin as in the other figures. In this arrangement of Fig. 5, the latch element 14 can be more conveniently manipulated by one standing at the side of the car, since he will not have to reach between the hitching pin and the car end to manipulate the latch element when swinging it to its release position.

The invention is not limited to the preferred embodiments but may be otherwise embodied within the scope of the following claims.

I claim:

1. A car coupling device comprising a hitching pin having a shoulder adjacent to its upper end, a support for the pin, a latch member pivotally mounted on a horizontal axis on said support, a projection carried by the latch member and movable into latching position above the shoulder when the latch member is swung in one direction, and means for holding the projection in its latched position to limit upward movement of the pin, the latch member being manually movable in the opposite direction to release position, said holding means comprising an extension on the latch member at that side of the pivotal support which is opposite said projection, and a stop below said extension for positively limiting downward movement of said extension.

2. A car coupling device comprising a hitching pin having a shoulder adjacent its upper end, a support for the pin, a latch member pivotally mounted on said support, on a horizontal axis located in a plane above said shoulder, a downwardly-sloping projection carried by the latch member in position to overlie the shoulder when the latch member is in one position, a counter weight on the latch member extending to that side of the pivot which is opposite said projection, and serving to normally hold the latch member with its projection in overlying relation to said shoulder, and a stop below said counter weight for positively limiting downward movement of said counter weight.

3. A car coupling device comprising a hitching pin having a shoulder adjacent its upper end, a support for the pin, a latch member pivotally mounted on said support, on a horizontal axis located in a plane above said shoulder, a downwardly-sloping projection carried by the latch member in position to overlie the shoulder when the latch member is in one position, and a counter weight on the latch member extending to that side of the pivot which is opposite said projection, and serving to normally hold the latch member with its projection in overlying relation to said shoulder, said projection being so sloped that the shoulder of the pin will engage the same and swing the latch member in opposition to the counter weight when the pin is being inserted into its coupled position, said support acting as a stop for positively limiting downward movement of said counter weight.

4. A car coupling device comprising a hitching pin having a shoulder adjacent its upper end, a support for the pin, a latch member pivotally mounted on said support, on a horizontal axis located in a plane above said shoulder, a downwardly-sloping projection carried by the latch member in position to overlie the shoulder when the latch member is in one position, and a counter weight on the latch member extending to that side of the pivot which is opposite said projection, and serving to normally hold the latch member with its projection in overlying relation to said shoulder, a portion of the latch member being extended to serve as a lever by which the latch member may be swung to inoperative position when it is desired to remove the hitching pin, said support acting as a stop for positively limiting downward movement of said counter weight.

5. A car coupling comprising a draw bar, a link, a hitching pin extending through the draw bar and the link, a shoulder adjacent the upper end of the hitching pin, a latch member pivotally mounted on the draw bar, a projection carried by the latch member and movable into latching position above the shoulder when the latch member is swung in one direction, and an extension on the latch member extending to that side of the pivot which is opposite said projection for holding the projection in its latched position to limit upward movement of the pin, the latch member being manually movable in the opposite direction to release position, said shoulder being disposed circumferentially of the axis of the pin, whereby it will be engaged and held by said projection at any rotative position of the pin, said draw bar acting as a stop for positively limiting downward movement of said extension.

6. A car coupling device comprising a hitching pin having a shoulder adjacent its upper end, a support for the pin, a latch member pivotally mounted on said support, a projection carried by the latch member and movable into latching position above the shoulder when the latch member is swung in one direction, an extension on the latch member extending to that side of the pivot which is opposite said projection for holding the latch member with its projection in latching position to limit upward movement of the pin, and means for automatically pushing the latch member to its release position during insertion of the pin to its seated position in a coupler, the latch member being thereafter automatically returned to its latching position, said support acting as a stop for positively limiting downward movement of said extension.

WILLIAM R. STAMLER.
